CLAIM

The ornamental design for a support rail for a food pan, as shown and described herein.

DESCRIPTION

FIG. 1 is a top perspective view of a support rail for a food pan illustrating our new design;

FIG. 2 is a bottom perspective view of the design of FIG. 1;

FIG. 3 is a side view of the design of FIG. 1;

FIG. 4 is a side view of the design of FIG. 1;

FIG. 5 is a front view of the design of FIG. 1;

FIG. 6 is a rear view of the design of FIG. 1;

FIG. 7 is a top view of the design of FIG. 1;

FIG. 8 is a bottom view of the design of FIG. 1;

FIG. 9 is a top perspective view of the design of FIG. 1 in use; and,

FIG. 10 is a bottom perspective view of the design of FIG. 1 in use.

The broken lines represent portions of the structure that form no part of the claim.
